HATCH PULL

Elmer F. Rinke, Utica, Mich.

Application June 11, 1956, Serial No. 41,836

Term of patent 7 years

(Cl. D10—8)

Fig. 3.

Fig. 1.

Fig. 2.

Fig. 1 is a front elevational view of a hatch pull showing my new design.

Fig. 2 is a side view showing the hatch pull in its outward position.

Fig. 3 is a top view of the hatch pull.

I claim:

The ornamental design for a hatch pull, as shown.
